UNITED STATES PATENT OFFICE.

JOHN H. GUEST, OF BOSTON, MASSACHUSETTS.

SUPPLY SYSTEM FOR ELECTRIC RAILWAYS.

SPECIFICATION forming part of Letters Patent No. 537,196, dated April 9, 1895.

Application filed June 18, 1894. Serial No. 614,872. (No model.)

To all whom it may concern:

Be it known that I, JOHN H. GUEST, a citizen of the United States, and a resident of Boston, in the county of Suffolk and State of Massachusetts, have invented a certain new and useful Improvement in Electric Railways, of which the following is a specification.

My invention relates to electric railways wherein the working conductor from which the car takes up current is divided into sections which are insulated from one another and from the source of power current and are provided with automatic switches that are actuated to close the connection with the source as the car enters the section and are opened after the car leaves the section.

One part of my invention relates to the means for controlling the operation of said switches, and is designed particularly as an improvement upon those plans wherein an actuating magnet on the car operates upon an armature connected to the switch on the permanent way. It has heretofore been proposed to hold the armature in circuit closing position (after the magnet has passed over and lifted it), by the attraction between the armature and a piece of iron or steel against which it is drawn by the action of said magnet when it closes the switch, but in this plan the armature is liable to be jarred loose and gravity or other retraction will thereupon return the armature to normal position and break the circuit. This may happen, obviously, before the car has left the section in which case the car would lose current. Another objection to this plan is that the attraction between the armature and the iron piece is depended upon to hold the contacts of the switch firmly against one another, but it does not always do this strongly enough to preserve good contact and prevent burning. My present invention aims to overcome these objections and consists essentially in the combination with the magnet on the car and the armature and switch on the road-bed, of an electro-magnet which exerts a mechanical pull on said armature to hold it in circuit closing position after being thrown to such position by the magnet on the car, said magnet on the road-bed being in a circuit closed by the switch. I prefer to employ for this purpose a solenoid magnet or magnet having a

movable core which is connected to the armature of the switch. I mount the magnet so that its core will slide in a horizontal line and therefore tend to retain the position in which it is placed by the action of the magnet on the car. Being so mounted the switch cannot be readily jarred loose at its contacts, nor will it tend to leave its circuit closing position even if the circuit should be momentarily interrupted on the car or at the contact of the collector with the working conductor.

Another feature of my invention consists in the combination with the devices thus far described, of a second solenoid magnet also mounted to work in a horizontal line and having its core connected to the same switch. The latter magnet is the unsetting magnet of the switch and is in a circuit closed when the car reaches another section of working conductor. In the preferred arrangement of circuits the car at each section of working conductor controls the circuits of unsetting magnets at front and rear of said section respectively, as described in my prior application for patent, Serial No. 500,858, filed February 20, 1894.

Another feature of my present invention relates to a working conductor composed of a metal cover plate for the conduit or boxing of the electric switches and various conductors of the system, and consists essentially in providing said metal cover plate with an upwardly projecting edge or lip to hold in place a surface layer of applied insulation of any desired kind which leaves the said cover unexposed for electric contact except at the edge engaged by the trolley or collectors on the car.

Another feature of the invention consists in using two lines of working conductors forming, respectively, the two poles of the supply source but arranged to have the ends of the sections of one line break joint with the other line.

My invention consists also of the details of construction and combinations of devices more particularly specified in the claims.

In the accompanying drawings:—Figure 1 is a longitudinal vertical section through a portion of my conduit and one of the electrical switches taken in the plane represented by the line 1 1, Fig. 2. Fig. 2 is a transverse section through said conduit and switch taken in the plane represented by the line 2 2, Fig.

1. Fig. 3 is a side view of the current collector. Fig. 4 is a diagram showing the arrangement of contact plates. Fig. 5 is a transverse section of a modified form of conduit. Fig. 6 is a diagrammatic representation of several successive sections of my system. Fig. 7 is a like representation of the circuits and apparatus on the car; and Fig. 8 is a diagram of a modification in the system of circuits.

A indicates the conduit of iron or other material and C, is the transverse tie or sleeper upon which it rests and to which it is secured. The conduit A, contains the conductors and the casing for the switches and is preferably provided at its bottom with the insulation G, consisting, if desired, of a stringer of wood. To the sides of the box may also be applied two longitudinal stringers G', against which the edge of the casing containing the switches rests. The switch boxes or casings are shown at B. Two lines of boxes are indicated to provide for a double line of working conductors. Each switch box may be bolted against the side of the casing as indicated.

The working conductors of the system are formed by the cover plates a and a' , which are fastened to the boxes B, and have longitudinal extensions of proper length to give the desired length of working conductor. Each extension may have a foot a^2 , to support it. The ends of the working conductors are separated from one another by spaces which may be filled in or not, as desired, with insulation. The covers a , a' , form a cover to the conduit as well as to the switch boxes themselves and are engaged by suitable collectors L, L', carried by the car. Two pairs of these collectors are shown to provide for the double line of working conductors, one line forming one terminal and the other the other electrical terminal of the supply source. The collectors engage with an upturned lip or edge of the cover plates a , a' , as shown, while the remainder of the surface of the plate is covered with insulation b, which protects the cover from accidental electrical contact by foreign objects excepting at the working edge. The upturned lip or edge serves to prevent displacement of this insulating surface which latter may be, if desired, a wooden planking or may be of any other desired nature. The wooden planking is preferably arranged to cover the breaks between the sections so that dirt cannot enter through the spaces.

In the arrangement shown in Fig. 2, the planking is fastened between the top edge of the conduit A, and the upturned edge of the cover plate, being firmly secured by the bolts which draw the switch box against the sides of the conduit.

The collectors L, L', may be wheels, or may be of other construction, and are preferably all mounted on a common support V, consisting of a plate of spring metal which may be so mounted upon the car as to allow a spring action to the wheels of the collector.

The two lines of working conductors a , a' , break joint as indicated in Fig. 4, the space between the sections of one line being arranged opposite the unbroken part of the other line. As the collector wheels are all mounted on a common support no jar will ensue when a collector wheel passes a joint or space between the sections of working conductor in either of the lines.

In the system herein described each switch or each section of working conductor controls the connection of the second section to the rear, the purpose being not to operate under any circumstances upon the next switch to the rear while the trolley or collector is bearing thereon since by so doing the switches in such section would be liable to spark and burn. By taking the second section to the rear, however, off of which section the trolley will certainly have passed, no sparking can be produced in the switches of such section since the circuit through such section will have already been opened. In this system it is practically necessary to use three sections of working conductor to each car length that at no time may there be any live or connected section of working conductor projecting from beneath the car. It will be obvious, however, that if the section of conductor on the opposite side of the system, which is at any time opposite the live section, be not connected to the power return then no damage would ensue from any person or object touching both said sections at the same time.

In my system the return connection is made by sections of working conductor normally insulated from such return and by alternating them with the sections on the opposite side it will be seen that it is permissible to have a portion of a section on one side of the system exposed from beneath the car without serious danger. It, therefore, becomes feasible to lengthen the individual sections and to employ no more than two rails to the car length if the sections be alternated as described on the opposite side of the system instead of three sections to the car length as is necessary if they do not break joint. When two rails to the car length are employed with the sections on opposite sides breaking joint and the second section to the rear is automatically disconnected when the car establishes connection with the section ahead, it will be found that although at times one half the length of a connected rail may project either before or behind the car and on one side or the other thereof, nevertheless, at no time will the section on the opposite side which is exposed be at the same time connected to the main conductor and hence no damage can ensue.

The collectors are connected on the car to the terminals of the motor typified at M, and included in the circuit is an electro-magnet T, which operates on the switches in the boxes.

The lips or upturned edges forming the longitudinal rib which constitute the working

conductors may be arranged as shown in Fig. 2, with the open space between them, or may be arranged near the edges of the conduit, as indicated in Fig. 5, and the whole space between them covered by the planking or other insulation *b*, thus covering not only the space between the ends of the plates in the same line but also the longitudinal space between the two lines.

10 R, is an armature in the switch box. This armature is operated upon by a pole of the magnet T, and being drawn up thereby closes a connection between the working conductor formed of the cover plate and the conductor 15 27, extending from one pole of the power source. The armature may be arranged with its free end opposite a plug N, of iron, which passes through the cover plate and is supported in a bushing of non-magnetic material 20 when said cover plate is made of iron. The switch operated by armature R, may consist of a spring attached thereto and adapted to make contact with the cover plate; the armature itself being connected through a suitable bearing with the conductor 27, running 25 through the line of conduit, but as to this part of the apparatus my invention is capable of many variations, the only essential being that the armature R, which is drawn up 30 by the magnet T, should be properly connected to some switch that will close the desired connection between 27, and the working conductor. As soon as the armature is drawn up it closes the connection and establishes a circuit 35 through the coil 20, of an electro-magnet whose core is indicated at I. The core I, is thereby drawn to one side and being connected with the armature R, holds the switch in circuit closing relation. This mechanical connection with the switch may be made by an arm *k*, extending from the armature lever R, and engaging with the core as clearly shown. The armature itself has, preferably, a suitable counterbalance *w*, and is pivoted upon a 40 bracket secured to a tube H, preferably of brass on which the coils of the electro-magnets are wound. The tube H, is supported in heads *i*, of some insulating material, and is slotted at the point where the arm *k*, passes 45 through for engagement or connection with the cores. At I', is another core attached to and forming a part of core I, and provided with coils 21, 22, wound upon the tube H, and serving, when traversed by a current, to pull 50 the core I', and core I, in a direction to open the switch. The core I', may be secured to I, as indicated, or the two may be formed of one piece of iron. These cores both move as 55 shown in a horizontal line and will retain any position in which they are placed by the influence of the electric current, unless moved from that position by some positive force.

As described, the armature lever R, is practically balanced and when the core I, operates on it to close a circuit, the connection will remain closed until the core I', moves the switch in the opposite direction. By this ar-

angement the position of the switch is not liable to disturbance from jars or shocks nor will it leave the position in which it is placed 70 by the influence of the magnet T, even though the circuit through the coil around I, should momentarily fail either by interruption of the circuit designedly on the car or by the collector failing momentarily to preserve connection with a section of working conductor. 75 The connection of the coil 20, may be made in any desired way with the conductor 27, at one of its terminals as indicated in Fig. 6, its other terminal being connected with lever R, 80 for instance through its pivot as indicated in Figs. 1 and 6, thus connecting the armature R, with the feeder 27. The coils 22 and 21, as indicated in the diagram, are connected at one end with the conductor 27, while the other 85 end of coil 21, extends two sections to the rear and connects with an armature R and the other end of coil 22, extends two sections in advance and there connects with an armature R. By this arrangement, on the closure of 90 circuit by any armature R, a connection from the working conductor 27, will be established through a coil 22, for a section at the rear of said switch and through a coil 21, for a section to the front, as described in my application before referred to. As shown the sections whose coils 21 and 22, are thus included in circuit are located at the second section in the rear of the active section and the second section in advance thereof but they may be 100 at a greater or less distance as desired. These coils 21, 22, operate as coils of a resetting magnet which opens the switch of a section which the car has left and also prevents the closure of a switch for a section in advance of the car 105 by any car which might be approaching. The arrangement also permits the car to be run in either direction at pleasure.

In the operation of my device the magnet T, suitably supported on the car will act on 110 the armature R, and close the switch thereby closing the connection to the section of working conductor and also energizing core I, of the electro-magnet which latter will thereafter firmly hold the contacts of the switch together after the magnet has passed beyond a position where it may influence the armature. 115 So far as concerns this operation of the devices it is obviously immaterial whether the magnet be constructed as a solenoid with its 120 core arranged to work in a horizontal line or not. Any arrangement of electro-magnet might be employed which would operate mechanically on the armature R, and the switch connected thereto to retain or hold the same 125 in position after the influence of the magnet T, had ceased.

In prior arrangements where the magnet T, has been used for operating on the armature, the latter has been retained in its position 130 simply by the attraction between itself and a piece of iron, which arrangement is subject to the objections before noted.

While I have described the use of a plug or

piece of magnetic material N, I do not wish to be understood as limiting myself to the employment of the same since the armature R, might be operated upon through the direct influence of the magnet on the vehicle instead of through the intervening piece of magnetic material.

It will be understood that the two wheels L, L, form together a common collector or trolley device adapted to bridge the spaces between sections of working conductor, as do the wheels L', L'. It is preferable to so arrange each collector with reference to the magnet that the armature shall be drawn up and the switch closed before the collector engages the corresponding section.

While I have described the use of two lines of switches, one for each line of cover plate, it is obviously not necessary to use switches for both lines, since one line might be connected to the source at all times substantially as indicated in Fig. 8, but to lessen leakage and danger I prefer to use switches for both lines.

25 When an insulated power return wire is employed, as hereinbefore described, in connection with normally insulated sections of working conductor and automatic switches therefor, I not only lessen leakage and the 30 danger of damage to neighboring water and gas pipes by electrolytic action, but also obtain a system wherein there is freedom from danger by any temporary exposure of a positive section of working conductor on the surface of the street and any accidental contact therewith while alive.

I am aware that it has been before proposed to use sections of working conductor for the positive side and automatic switches for connecting the same with an insulated power main but I am not aware that it has been also proposed to employ in connection therewith an insulated power return wire and automatic switches for connecting the latter with sections of working conductor thereby making it possible when the sections are on the opposite side of the system and alternated or made to break joint to increase the length of the sections without material danger from retaining the connection with a section after it has been partially exposed by the car passing over it.

What I claim as my invention is—

1. In an electric railway system, the combination with the magnet on the car, of an armature therefor on the road-bed, a switch connected to said armature for closing the connection between a supply wire and a section of working conductor, and an electro-magnet 60 having its coil in said connection and having its movable portion mechanically connected with said armature and acting to hold the switch closed after being closed by the magnet on the car, substantially as set forth.

65 2. In an electric railway system, the combination with the magnet on the car, of an armature therefor on the road-bed, a switch con-

nected to said armature and located in a circuit connection between a supply wire and a section of working conductor, and an electro-magnet whose movable portion is mechanically connected to the armature of the car magnet to hold the switch closed when closed by the car magnet and having its coil in a circuit completed by the closure of said switch, substantially as set forth.

70 3. In an electric railway system, the combination with the magnet on the car, of an armature therefor, a switch connected to said armature for closing the connection for a section of working conductor, and a solenoid magnet also connected to said switch, and having its core arranged to work in a horizontal line, said solenoid having a coil in a circuit completed when the switch is closed, as 85 and for the purpose described.

4. In an electric railway system, the combination with sections of working conductor normally dead, of a switch for connecting each section with a supply wire, and a double 90 solenoid having its cores mechanically connected and mounted to work in a horizontal line, one coil of said solenoid being placed in circuit by the switch when closed and the other being in a circuit closed from another 95 section of working conductor.

5. In an electric railway system, the combination with a working conductor, of a switch, an armature connected thereto, an operating magnet on a car, and a double solenoid having connected cores one provided with a winding in a circuit closed by the switch, and the other having two windings in circuits to sections of working conductor at front and rear respectively of said switch.

100 6. In an electric railway system, two lines of working conductors composed of the metal cover plates for two lines of automatic switches contained in a suitable conduit, said cover plates being provided with continuous ribs or flanges forming the working conductors engaged by the collector and said ribs or flanges being thoroughly insulated from each other and from the ground.

110 7. In an electric railway system, two lines of working conductors composed of the metal cover plates for two lines of automatic switches contained in a suitable conduit, said cover plates being provided with continuous ribs or flanges forming the working conductors engaged by the collector and having a continuous surface layer b, of insulating material covering the longitudinal space between the two lines of cover plates as well as the space between the ends of the plates in 120 each line.

120 8. In an electric railway system, an electric conduit having two lines of cover plate insulated from one another and each having a projecting rib or flange forming a working conductor, said two lines forming a double sectional working conductor connected through the collector with the two poles of the motor, and a protective surface of insulation

covering said plates excepting at the exposed rib or flange.

9. In an electric railway system, the combination, substantially as described, of two lines of working conductor beneath the car, exposed at the street surface and divided into sections and forming respectively the positive and negative sides of the system, the sections on one side of the system being arranged to
5 break joint with the sections on the other, and automatic switches for closing the con-

nection between the sections of working conductor and the power circuit and disconnecting a section to the rear of the car, as and for the purpose described.

Signed at New York, in the county of New York and State of New York, this 8th day of June, A. D. 1894.
